M. G. DELANEY.

FILM REEL

APPLICATION FILED FEB. 21, 1914. RENEWED MAY 8, 1915.

1,144,697.

Patented June 29, 1915.

UNITED STATES PATENT OFFICE

MICHAEL G. DELANEY, OF DETROIT, MICHIGAN, ASSIGNOR TO THE NORTHERN SALES CO., OF TOLEDO, OHIO, A CORPORATION OF OHIO.

FILM-REEL.

1,144,697.

Specification of Letters Patent. Patented June 29, 1915.

Original application filed December 12, 1912, Serial No. 736,347. Divided and this application filed February 21, 1914, Serial No. 820,215. Renewed May 8, 1915. Serial No. 26,903.

To all whom it may concern:

Be it known that I, MICHAEL G. DELANEY, a citizen of the United States of America, residing at Detroit, in the county of Wayne and State of Michigan, have invented certain new and useful Improvements in Film-Reels, of which the following is a specification, reference being had therein to the accompanying drawings.

This invention relates to film reels for moving picture machines of the type wherein the film is delivered if desired, at the center of the reel and withdrawn from the rim thereof, this being a divisional application of my co-pending application Serial #736,347, filed December 12, 1912, for film reels.

The invention consists in the matters hereinafter set forth and more particularly pointed out in the appended claims.

In the drawings: Figure 1 is a view partially in side elevation and partially broken away and in section, of a form of reel that embodies the features of the invention. Fig. 2 is a view in transverse section taken on or about line II—II of Fig. 1. Fig. 3 is a sectional elevation looking at the inside of one of the plates showing the mechanism for locking the front and back plates together; Fig. 4 is a partial elevation of the cover showing the bayonet lock.

As herein shown, the reel is formed of a back plate 1 that is fixed on a tubular shaft 2 adapted to be rotatably mounted on any journal and turned by an application of a proper crank to the notched ends of the shaft. A plate 4 is journaled on the shank in parallel relation to the plate 1 and may be locked therewith as by a cam 8 on the lever 7 controlling the same mechanism shown in the other application Serial No. 736,347, namely a spring pressed dog 37 and the notched periphery of the flange 5 on the shaft or other means for detachably locking the parts to turn together, may be used.

In this form of the device, a film as indicated at 25, may be inserted from the outside under a guide roller 26 to be drawn around a plurality of other guide rollers 27 that are carried on arms 28, the latter being spring-projected in any suitable fashion with the journals of the rollers playing in slots 21. The free end of the strip of film is drawn

out through a slot indicated at 30 in the 55 cover 31 of the reel and is held thereby a spring finger 32. Thereafter the film is wound on by turning the plate 1 on its journal. Afterward the cover 31 is removed by partial rotation so that the heads of the pins 60 register with the enlargements of the slots which form the bayonet lock 23, the plates 1 and 4 are then locked to turn together, and the film drawn off from the reel in the usual manner by means of the lever latch 7. In 65 other words, this construction is particularly adaptable for feeding the film into the side opening of the reel and drawing it off from the periphery in a reverse direction to the method of winding shown in the original 70 application, although this is not a necessary feature of the device.

As a result of this construction, the reel is readily filled and then unloaded without having to rewind the film, thereby saving 75 time as well as wear and tear on the film.

Obviously, changes and details of construction may be made without departing from the spirit of the invention and I do not care to limit myself to any particular 80 form or arrangement of parts.

I claim as my invention:

1. The combination with the wall of a film magazine provided with an opening therein, of a film reel comprising a back 85 plate secured on a bearing member, a front plate provided with an opening, and journaled on the bearing member, means for securing the front plate to the wall with the respective openings in register, manually 90 operable means for locking the plates and bearing member to turn together, a film guide extending from the opening of the front plate into concentric relation to the bearing member between the plates, a flanged 95 cover adapted to be locked on the back plate and to encircle the front plate, and means for yieldingly maintaining a film applied to the reel in operative relation to the guide through the cover opening. 100

2. A film reel comprising a bearing member adapted to be rotatably mounted on a suitable support, a back plate secured to the member, a front plate journaled on the member and provided with an opening means on the front plate adapted to hold a film that passes through the opening in operative relation to the bearing member and plates, a 105

cover removably secured on the back plate and encircling the front plate with a film opening therethrough, and means for locking the plates and member to turn together.

5 3. A film reel comprising a bearing member adapted to be rotatably mounted on a suitable support, and provided with a fixed side plate, a complementary side plate rotatably mounted on the bearing member in spaced relation to the other plate and provided with a film opening, guiding means between the plates for holding a film that passes through the plate opening in oper-

ative relation to the plates and bearing member, a cover detachably secured on the fixed side plate around the other plate and provided with a film opening, and means for locking the rotatable plate to turn with the bearing member.

In testimony whereof I affix my signature 20 in presence of two witnesses.

MICHAEL G. DELANEY.
